CLAIM

The ornamental design for a killer whale life vest, as shown and described.

DESCRIPTION

FIG. 1 is a right side view of the killer whale life vest of the present invention, the left side view being a mirror image thereof;

FIG. 2 is a front view thereof;

FIG. 3 is a back view thereof;

FIG. 4 is a top view thereof; and,

FIG. 5 is a bottom view thereof.

The broken lines are for purposes of illustration only and form no part of the claimed design.

The drawing is lined for color (black).

The hatch marking shown in the drawings represent a pattern simulating "killer whale" markings.
